US00D533779S

(12) **United States Design Patent** (10) **Patent No.:** **US D533,779 S**
Schmidtner et al. (45) **Date of Patent:** **** Dec. 19, 2006**

(54) **RECLOSEABLE CUP LID**

(75) Inventors: **Alois A. Schmidtner**, Hellertown, PA (US); **Jonathan E. Rush**, Mt. Bethel, PA (US)

(73) Assignee: **Fort James Corporation**, Atlanta, GA (US)

(**) Term: **14 Years**

(21) Appl. No.: **29/214,791**

(22) Filed: **Oct. 8, 2004**

(51) LOC (8) Cl. **09-07**

(52) U.S. Cl. **D9/449**

(58) **Field of Classification Search** D9/454, D9/449, 447, 445, 439, 438, 435, 452, 453; D7/638, 511, 510, 392, 392.1; D3/323; 220/270-271, 220/709, 718, 781, 575, 715; 215/254

See application file for complete search history.

(57) **CLAIM**

The ornamental design for a reclosable cup lid, as shown and described.

DESCRIPTION

A portion of the disclosure of this patent document contains material to which a claim for copyright is made. The copyright owner has no objection to the facsimile reproduction by anyone of the patent document or the patent disclosure as it appears in the Patent and Trademark Office patent file or records, but reserves all other copyright rights whatsoever.

FIG. 1 is a top perspective view of the reclosable cup lid of this invention with the sliding closure panel thereof in its open position;

FIG. 2 is a top view of the reclosable cup lid of FIG. 1

FIG. 3 is another top view of the reclosable cup lid of FIG. 1, wherein the closure panel is shown in its closed position;

FIG. 4 is a bottom perspective view of the reclosable cup lid of FIG. 1, with the closure panel shown in its open position;

FIG. 5 is a bottom view of the reclosable cup lid of FIG. 1, with the closure panel again shown in its open position;

FIG. 6 is a view in elevation of the Reclosable Cup Lid of FIG. 1 along line 6—6 of FIG. 2; and.

FIG. 7 is another view in elevation along line 7—7 of FIG. 2
